UNITED STATES PATENT OFFICE

93,091

DESIGN FOR A SEWING MACHINE

Charles E. Colegrove, Lakewood, Ohio, assignor
to White Sewing Machine Corporation, Cleve-
land, Ohio, a corporation of Delaware

Application December 11, 1933, Serial No. 50,037

Term of patent 14 years

To all whom it may concern:

Be it known that I, CHARLES E. COLEGROVE, a citizen of the United States, residing at Lakewood, in the county of Cuyahoga and State of Ohio, have invented a new, original, and ornamental Design for Sewing Machine, of which the following is a specification, reference being had to the accompanying drawing, forming a part thereof, in which

Fig. 1 is a front elevational view of a sewing machine embodying the present design;

Fig. 2 is an end elevational view thereof, looking from the right-hand side of Fig. 1, and

Fig. 3 is a top plan view.

The design comprises a sewing machine arm of modernistic outline. The sewing machine arm

includes a vertically extending standard or post having at its upper end a laterally and horizontally extending portion to the outer end of which is secured the face plate of the sewing machine. The standard or post and the laterally extending portion are of polygonal cross-section imparting to the design a modernistic appearance, while the outer end of the laterally extending portion is provided with outwardly divergent sides forming an enlargement interfitting and blending with the face plate.

I claim:

The ornamental design for a sewing machine substantially as shown and described.

CHARLES E. COLEGROVE.
